UNITED STATES PATENT OFFICE.

CHARLES J. KOTCHI, OF CHICAGO, ILLINOIS, ASSIGNOR TO KORO ELECTRIC CORPORATION, OF CHICAGO, ILLINOIS, A CORPORATION OF ILLINOIS.

HOLDER FOR ELECTRIC-WELDING ELECTRODES.

Application filed January 29, 1926. Serial No. 84,565.

This invention relates to improvements in holders particularly adapted, though not necessarily limited in its use, for holding electrodes, rods, or wires employed in arc welding, and one of the objects of the invention is to provide an improved device of this character which will be compact and simple in construction and adapted for ease in manipulation, and in which device the electrode or wire will be firmly held or clamped without the use of a screw or springs for clamping the wire.

A further object is to provide an improved device of this character embodying clamping members between which the rod or wire is held, the clamping members being slightly resilient, one with relation to the other, to compensate varying sizes of rods or wires.

A further object is to provide an improved device of this character in which the jaws or clamping members will be frictionally maintained in their relative adjusted position.

A further object is to provide in a device of this character an improved handle and improved means for securing one of the conductors to the device for passing a current through the electrode or wire.

To the attainment of these ends and the accomplishment of other new and useful objects as will appear, the invention consists in the features of novelty in substantially the construction, combination and arrangement of the several parts, hereinafter more fully described and claimed and shown in the accompanying drawing illustrating the invention, and in which—

Figure 1 is a front elevation of the device.

Figure 2 is a side elevation of Figure 1.

Figure 3 is a longitudinal sectional view taken on line 3—3 Figure 1.

Figure 4 is a rear elevation of Figure 1.

Figure 5 is a detail view of the friction creating elastic element.

Referring more particularly to the drawing, the numeral 10 designates generally a body portion, one end of which is provided with a goose-neck formation 11, to a portion of which is secured a jaw 12.

To the other end of the body portion 10 is secured a handle 13 which is of any suitable insulating material, and is tubular in construction to permit of one end of an electrical conductor 14 to pass therethrough.

The extremity of the conductor 14 is secured

in any suitable manner in electrical contact with the body 10, preferably by means of a clamping device 15 arranged in proximity to one end of the handle 13. The clamping device is preferably provided with its extremities 60 slotted as at 16 to receive binding screws 17 and assists in seating the conductor.

The body portion 10 may be of any desired length and configuration and slidably mounted thereupon is a movable jaw 18, in proximity to the jaw 12 to co-operate therewith for clamping a rod or wire 19 therebetween.

The jaw portion of the extremity 11 of the body is preferably of a slightly resilient nature so as to compensate rods or electrodes of 70 varying diameters.

The jaw 18 is slidably mounted upon the body 10 in any suitable manner, preferably by means of a screw or bolt 20 which passes through an elongated slot 21 in the body 75 portion of the jaw 18. The head 22 of the bolt is disposed adjacent a lateral face 23 of the body of the jaw 18, and disposed between the head or bolt and the face 23 is a washer like device 24 which contacts with 80 the surface 23. An elastic or resilient element 25, preferably in the form of a split spring washer, is disposed between the head 22 of the bolt and the element 24 and tends normally to create friction upon the surface 85 23 of the jaw 18.

The bolt is held in position preferably by means of a nut 26 engaging the extremity of the bolt and contacting with the other face of the body 10. The surface 23 of the 90 jaw 18 is beveled or inclined so that when the jaw 18 is moved in a direction toward the jaw 12, the stress of the resilient element 25 will be increased so as to cause the element 24 to frictionally bind upon the surface 23 and thereby clamp the body of the jaw 18 between the element 24 and the adjacent face of the body 10, to frictionally maintain the jaw 18 in its adjusted position with respect to the jaw 12.

When the jaw 18 is moved away from the jaw 12, the inclined surface 23 will cause the stress of the elastic element 25 and the element 24 upon the surface 23 to be decreased.

Any suitable means may be provided for sliding the jaw 18 upon the body 10. A simple and efficient means embodies a bell-crank lever 27 which is pivotally mounted as at 28 upon the body portion 10. A lug 29 110

is carried by one end of the bell-crank lever for pivotally connecting that end of the lever with the body portion of the jaw 18, preferably by passing into a recess or aperture 30 in the body of the jaw. Connected with the other end of the bell-crank lever is a handle 31 of any suitable insulating material, and this handle 31 is disposed in proximity to the handle 13 and in a convenient position for the operator while holding the tool.

By swinging the bell-crank lever 27 about its pivot 28 the jaw 18 may be given a sliding movement toward and away from the jaw 12.

With this improved construction it will be manifest that a simple and efficient device for holding an electrode or wire for electric welding will be provided, and the wire or electrode will be clamped in the holder without the use of springs or screws usually employed for clamping the electrode. As the jaw 18 is moved toward the jaw 12 the resilient elements 25 and 24 will co-operate with the inclined surface 23 on the jaw to automatically tighten or clamp the jaw 18 in its adjusted position.

By the provision of the inclined surface 23 on the body portion of the jaw 18, the wire or electrode may be readily released when desired by pushing the lateral surface of the electrode against the work or any suitable stop. This will cause the jaw 18 to readily yield and during such movement the bell crank lever 27 will be swung about its pivot 28 to permit of such movement of the jaw 18, thereby obviating the necessity of the operator using the other hand to swing the lever 27. This allows the operator to have one of his hands free for other purposes.

If desired an additional friction creating device embodying a spring washer 32 and an element 33 may be provided under the head 34 of the pivot bolt 28 for creating considerable friction between the bell-crank lever 27 and the adjacent face of the body portion 10 of the holder.

While the preferred form of the invention has been herein shown and described, it is to be understood that various changes may be made in the details of construction and in the combination and arrangement of the several parts, within the scope of the claims without departing from the spirit of this invention.

What is claimed as new is:

1. A holder of the character described including a handle, a fixed jaw, connected with the handle, a movable jaw co-operating with the fixed jaw, means for actuating the movable jaw, and means for frictionally maintaining the said movable jaw in its adjusted position with respect to the fixed jaw.

2. A holder of the character described including a handle, a fixed jaw connected with the handle, a movable jaw co-operating with the fixed jaw, means for actuating the movable jaw, and means for frictionally maintaining the said movable jaw in its adjusted position with respect to the fixed jaw, one of said jaws being slightly yieldable with respect to the other jaw to compensate varying sizes of rods or wire clamped by the jaws.

3. A holder of the character described including a handle, a fixed jaw connected with the handle, a movable jaw co-operating with the fixed jaw, means for actuating the movable jaw, means for frictionally maintaining the said movable jaw in its adjusted position with respect to the fixed jaw, and means for securing an electric conductor to the holder.

4. A holder of the character described including a handle, a fixed jaw connected with the handle, a movable jaw co-operating with the fixed jaw, means for actuating the movable jaw, means for frictionally maintaining the said movable jaw in its adjusted position with respect to the fixed jaw, and means for securing an electric conductor to the holder, the said conductor passing through the said handle.

5. A holder of the character described including a handle, a fixed jaw connected with the handle, a slidable jaw co-operating with the fixed jaw, an actuator for the movable jaw, and means for frictionally maintaining the movable jaw in its adjusted position, the said means including two contacting surfaces movable relatively one with respect to the other, one of said surfaces being inclined, and means for yieldingly maintaining such surfaces in contact and for slight lateral movement one with relation to the other.

6. A holder of the character described including a handle, a jaw connected with the handle, a slidable jaw co-operating with the first said jaw, an actuator for the slidable jaw, and means for frictionally maintaining the slidable jaw in its adjusted position, the said means embodying a cam like formation operating to cause a lateral pressure to be exerted upon a portion of the said slidable jaw.

7. A holder of the character described including a handle, a jaw connected with the handle, a slidable jaw co-operating with the first said jaw, an actuator for the slidable jaw, and means for frictionally maintaining the slidable jaw in its adjusted position, the said means embodying a cam like formation operating to cause a lateral pressure to be exerted upon a portion of the said slidable jaw, and means for causing the degree of such lateral pressure to increase as the said slidable jaw approaches the first recited jaw.

8. A holder of the character described in-

cluding a handle, a jaw connected with the handle, a slidable jaw co-operating with the first said jaw, an actuator for the slidable jaw, and means for frictionally maintaining the slidable jaw in its adjusted position, the said means embodying a cam like formation operating to cause a lateral pressure to be exerted upon a portion of the said slidable jaw, and means embodying a resilient element operating against a lateral face of the movable jaw for causing the said lateral pressure to increase as the slidable jaw approaches the first recited jaw.

9. A holder of the character described including a jaw, a handle connected therewith, a slidable jaw, a pivotally mounted element connected with the said sliding jaw for actuating it, an inclined surface connected with the slidable jaw, and a resilient element operating to create a lateral pressure upon the movable jaw and against said surface for frictionally maintaining the slidable jaw in its adjusted position.

10. A holder of the character described including a jaw, a handle connected therewith, a slidable jaw, a pivotally mounted element connected with the said sliding jaw for actuating it, an inclined surface connected with the slidable jaw, a resilient element, operating to create a lateral pressure upon the movable jaw and against said surface for frictionally maintaining the slidable jaw in its adjusted position, and means whereby the stress of the said resilient element may be varied.

11. A holder of the character described including a handle, a jaw connected with the handle, a movable jaw slidably connected with the first said jaw, a bell crank lever pivotally connected by one end with the sliding jaw for actuating it, an inclined surface formation connected with the slidable jaw, and a resilient element contacting with the said inclined surface and operating to frictionally maintain the said sliding jaw in its adjusted position.

12. A holder of the character described embodying a body portion, a jaw formation at one end thereof, a handle connected with the other end, a movable jaw slidable upon said body portion, a bell crank lever pivotally mounted upon the said body portion, one end of the lever being pivotally connected with the said movable jaw for actuating it, the other end of the lever being disposed adjacent the said handle, and means exerting a variable lateral tension upon the slidable jaw for maintaining it in its adjusted position.

13. A holder of the character described embodying a body portion, a jaw formation at one end thereof, a handle connected with the other end, a movable jaw slidable upon said body portion, a bell crank lever pivotally mounted upon the said body portion, one

end of the lever being pivotally connected with the said movable jaw for actuating it, the other end of the lever being disposed adjacent the said handle, and means exerting a variable lateral tension upon the slidable jaw for maintaining it in its adjusted position, there being an elongated slot through the body of the slidable jaw, the said means embodying a bolt connected with the first recited body portion and passing through said slot, and a resilient element disposed between the bolt and the said slidable jaw and exerting a lateral pressure upon the latter.

14. A holder of the character described embodying a body portion, a jaw formation at one end thereof, a handle connected with the other end, a movable jaw slidable upon said body portion, a bell crank lever pivotally mounted upon the said body portion, one end of the lever being pivotally connected with the said movable jaw for actuating it, the other end of the lever being disposed adjacent the said handle, and means exerting a variable lateral tension upon the slidable jaw for maintaining it in its adjusted position, there being an elongated slot through the body of the slidable jaw, the said means embodying a bolt connected with the first recited body portion and passing through said slot, and a resilient element disposed between the bolt and the said slidable jaw and exerting a lateral pressure upon the latter, the face of the slidable jaw that is engaged by said element being inclined.

15. A holder of the character described including a body portion, a handle connected with one end thereof, a goose-neck at the other end of the body, a jaw formation at the end of said goose-neck, a member slidable upon said body portion, a jaw formation at the end of the member, there being an elongated slot through said member, a bolt passing through the slot and engaging said body portion, a resilient element carried by the bolt and engaging a lateral face of the said member, and a bell crank lever pivoted to the said body portion, one end of the lever being pivotally connected with the member for sliding it upon the said body portion.

16. A holder of the character described including a body portion, a handle connected with one end thereof, a goose-neck at the other end of the body, a jaw formation at the end of said goose-neck, a member slid able upon said body portion, a jaw formation at the end of the member, there being an elongated slot through said member, a bolt passing through the slot and engaging said body portion, a resilient element carried by the bolt and engaging a lateral face of the said member, and a bell crank lever pivoted to the said body portion, one end of the lever being pivotally connected with the member for sliding it upon the said body portion,

the face of said member which is engaged by said element being inclined.

17. A holder of the character described including a body portion, a handle connected with one end thereof, a goose-neck at the other end of the body, a jaw formation at the end of said goose-neck, a member slid able upon said body portion, a jaw formation at the end of the member, there being an elongated slot through said member, a bolt passing through the slot and engaging said body portion, a resilient element carried by the bolt and engaging a lateral face of the said

member, a bell crank lever pivoted to the said body portion, one end of the lever being 15 pivotally connected with the member for sliding it upon the said body portion, said handle being tubular to receive an electric conductor, and a clamping device for the conductor connected with the said body portion adjacent the said handle. 20

In testimony whereof I have signed my name to this specification, on this 27th day of January, A. D. 1926.

CHARLES J. KOTCHI.
